CLAIM

The ornamental design for a pot or pan restraint with slotted base for engaging radial bars of recreation vehicle stove top grating, as shown.

DESCRIPTION

FIG. 1 is a perspective view of the pot or pan restraint; FIG. 2 is a bottom plan view of the restraint of FIG. 1; and

FIG. 3 is a side elevation view of the restraint of FIG. 1.

FIG. 1.

FIG. 2.

FIG. 3.
